(57) **CLAIM**

The ornamental design for a horseshoe, as shown and described.

DESCRIPTION

FIG. 1 is a bottom-isometric view of another embodiment of a horseshoe showing our new design;
FIG. 2 is a front view thereof;
FIG. 3 is a rear view thereof;
FIG. 4 is a side view thereof;
FIG. 5 is a top view thereof;
FIG. 6 is a bottom view thereof; and,
FIG. 7 is an enlarged view of area 7-7 in FIG. 6.
The broken lines in the Figures show environment for illustrative purposes only and form no part of the claimed design.
